UNITED STATES PATENT OFFICE.

HENRY W. FAUST, OF SEATTLE, WASHINGTON, ASSIGNOR TO SYBIL B. FAUST.

CONCENTRATOR.

1,275,235.

Specification of Letters Patent. Patented Aug. 13, 1918.

Application filed February 17, 1916. Serial No. 78,884.

To all whom it may concern:

Be it known that I, HENRY W. FAUST, a citizen of the United States, and a resident of Seattle, in the county of King and State of Washington, have invented certain new and useful Improvements in Concentrators, of which the following is a full, clear, and exact specification.

My invention relates to improvements in concentrators and has for its principal object to provide an improved and novel form of ore concentrator which embodies an improved form of pulsating plunger; to provide a multiple stage concentrator which requires a minimum of water; to provide an improved means of preventing swishing or wave action of the water in the concentrator. In concentrating plants the supply of water is frequently limited and economy in its use is of the utmost importance. My improved concentrator has been found to use a minimum of water in actual tests. The swishing of the water in the hutch interferes with the action of the plunger and causes imperfect pulsations, and eddies in the water adjacent the screens and consequently dead spaces on the screen. It is to overcome the above objections in concentrating that my machine is designed.

Other objects will appear as my invention is more fully explained in the following specification, illustrated in the accompanying drawings and pointed out in the appended claim.

In the drawings, Figure 1 is a front elevation of my concentrator with parts broken away. Fig. 2 is an end elevation with parts broken away.

Referring more particularly to the drawings, A and B indicate adjacent hutch compartments which are similar except that screens 1 are at different elevations. Each hutch is divided transversely by a partition 2 and a hopper bottom 3 which slopes toward the front of the hutch. Partition 2 does not extend down as far as bottom 3 but leaves a gate opening for the flow of water to the screen compartment of the hutch on one side of said partition from the plunger compartment on the other side. Screens 1 are provided with transverse bars 4 which control the action of water against the screen. An eccentric shaft 5 passes through the plunger compartments of the hutch and is provided with a drive pulley 6. Plungers 7 are provided one in each

plunger compartment. The plungers are pivotally and adjustably hinged or suspended at one end from a rod 8 which is parallel with shaft 5. Near the other end a vertical cam standard 9 is secured which supports an antifriction cam roller 10 in an oil bath cup 11 at its upper end. Cam rollers 10 bear against adjustable eccentric cams 12 which are secured to shafts 5. Adjustable springs 13 are attached to the front of the plungers and to the hutch cover. A water supply trough 14 supplies water to the plunger compartments and an ore feeding box 15 supplies ore to the first screen. A flexible packing strip 16 is secured to the rear edge of the plunger and bears against the back of the hutch so as to keep the joint between the back of the plunger and hutch tight to water on the back stroke. This prevents splashing and swishing and enables the device to operate with less water than otherwise. The operation of my concentrator is as follows:

Ore and water are supplied as previously described. The ore bed on the screens is maintained at a predetermined depth by regulating the supply of ore and water. The water level is maintained at a little above the top of the ore bed. The flow of ore and water is continuous from the first screen toward the second, etc. The ore is floated from one screen to the next over a baffle 17. The eccentric cams are set to give the desired stroke to the plungers at the particular speed of shaft 5. The cams throw the plungers downwardly which transmits an impulse to the water in the hutch. The flow of water from the plunger compartment to the screen compartment forces the water up through the screen, from beneath which raises the ore bed and allows it to float toward the lower screen and at the same time shakes the fine material of the higher specific gravity through the screen and into the hutch. If the gangue is the lighter, the ore will pass through the screens and the gangue will tail off through a spout 18. The action of my improved plunger which is not positively connected to the cam (as is usual) obviates the positive return stroke of the plunger which causes a heavy lift or vacuum on the water surface adjacent the plunger. It is believed that the sudden positive lift of the plunger jerks the water surface too suddenly and causes swishing and

wave action to set up with a resulting disturbance throughout the entire body of water. The disturbance or eddies in the water disturbs the ore bed and causes unevenness in the work of the screens and frequently causes portions of the screen to be inactive. In concentrating ores in which the metal and gangue are of nearly the same specific gravity, it requires very little disturbance of the ore bed to seriously affect the results obtained. My concentrator has been found particularly well adapted for tungsten ores which are very valuable and difficult to separate. The spring returns the plunger to normal position with a movement which suits the work in hand particularly well and gives much better results than a positive acting return movement. It is further believed that the hinged action of the plunger crowds the water downward and gives it a more even pulsation with less disturbance than the slap stroke of a direct acting eccentric plunger. My concentrator may be built either single or double, that is with plungers on one or both sides of the screens.

While I have shown a particular form of

embodiment of my invention, I am aware that many minor changes therein will readily suggest themselves to others skilled in the art without departing from the spirit and scope of the invention and I therefore desire to avoid being limited to the exact form shown and described.

Having described my invention, what I claim as new and desire to protect by Letters Patent, is—

In an ore jig, a hutch adapted to contain a screen, water pulsating means, and water admission means, said water pulsating means including a plunger means adjacent the hutch wall for pivotally supporting the plunger to permit a bodily movement of such plunger about the pivot, whereby to move one edge of such plunger toward the hutch wall in the operating stroke thereof and from the wall on the opposing stroke, a sealing strip on such plunger edge, means for positively moving the plunger on its operative stroke about its pivot, and independent spring means for returning the plunger.

HENRY W. FAUST.
